COMBINATION GREEN MARKER AND ADVERTISING DEVICE

Filed Oct. 25, 1930

UNITED STATES PATENT OFFICE

STURGILL F. RATLIFF, OF MOBILE, ALABAMA

COMBINATION GREEN MARKER AND ADVERTISING DEVICE

Application filed October 25, 1930. Serial No. 491,277.

This invention relates to an accessory or appliance for use and association with golf greens on regulation as well as miniature golf courses.

5 In carrying the inventive conception into actual practice, I have evolved and produced a simple and economical structure which is primarily designed for advertising purposes, but is equally useful as a convenient accessory 10 for participants in the game of golf.

Briefly stated, the invention is characterized by a suitable standard, located within the vicinity of the putting green, there being a table-like head on the upper end of said 15 standard and said head being of a composite nature characterized by several distinct structural features to aid in the keeping of scores, to function as a green marker, and to display diversified forms of advertisements.

20 The particular details and their relative arrangement and association will become more readily apparent from the following description and drawings.

In the drawings:

25 Figure 1 is a perspective view showing the device in position.

Figure 2 is a sectional view of the head structure.

Figure 3 is a cross section.

30 Referring to the drawings, in Figure 1, the numeral 4 designates the terminal end of the fairway, while the numeral 5 designates the associated putting green.

In carrying the invention into practice, I 35 have found it expedient and practical to utilize an appropriate supporting standard or post as at 6. This is preferably embedded in the ground within convenient reach of the green 5 and preferably located on the side of 40 the green constituting the approach to the next teeing ground of the succeeding fairway.

The head structure is of a composite nature. In the first place, it embodies a base- 45 board or plate 7. This is fastened by a screw or the like 8 to the upper end of the standard. The standard is preferably mitered at this point as to dispose the base in an inclined tablet-forming position. This facilitates con- 50 venient display of the advertising means and

provides an appropriate support for facilitating writing of the score on the usual score-card (not shown).

At the upper end of this base is a riser 9 which is here provided with distinguishable 55 indicia. The numeral 10 has its lead line extending to the ordinal 6. It is intended to provide a marker showing the particular number of the fairway in use at the time. The indicia 11 represents the par for this particu- 60 lar No. 6 green.

The numeral 12 designates generally a 65 cover which is hingedly mounted along one longitudinal edge of the board 7 as indicated at the point 13. The cover comprises a suitable frame 14 provided with a transparent glass panel 15. Clamped or otherwise secured between the glass panel and the upper side of the base 7 is an advertising card, label, or the like 16. This is designed to afford advertising while the participants engage in marking their score on their score-cards. Incidentally, this inclined head structure provides a suitable card resting surface on which the score-card may be conveniently laid so as 70 to enable the participant to conveniently 75 mark the score on said card.

The numerals 17 designate writing instruments or pencils secured permanently in place by chains 18 to facilitate marking of 80 the score on the usual score-card. This obviates the necessity of the participants carrying pencils.

A structure of this kind is of a multiple 85 functional nature. It serves primarily as an advertising panel for displaying appropriate advertisements on the golf course. Secondly, it provides a convenient inclined tablet or table on which the score-card may be rested for marking the score. Thirdly, it provides 90 a convenient marker for the green, and indicates the par for a particular green.

Moreover, the structure affords conveniently located pencils to expedite scorekeeping.

95 It is thought that persons skilled in the art to which the invention relates will be able to obtain a clear understanding of the invention after considering the description in connection with the drawings. Therefore, a more lengthy description is regarded as un- 100

necessary. Minor changes in shape, size, and rearrangement of details coming within the field of invention claimed may be resorted to in actual practice if desired.

5 I claim:

An advertising device and score card supporting table for a golf course comprising a post having an inclined upper end, a board connected to said upper end at the center of 10 the board, a frame hinged at one edge to said board, a transparent member in the frame, a vertically arranged plate connected at its 15 lower edge to the top edge of the board, the upper edge of the board and the upper edge of the frame being bevelled to engage the front face of the plate, indicia on the front face of the plate.

In testimony whereof I affix my signature.

STURGILL F. RATLIFF.
